ARTIFICIAL TOOTH

Jacob A. Saffir, Kew Gardens, N. Y., assignor to
 Dentists' Supply Company of New York, New
 York, N. Y., a corporation of New York

Application April 10, 1943, Serial No. 482,558

13 Claims. (Cl. 32—8)

This invention relates to the art of prosthetic dentures and particularly to the artificial teeth comprising the same, embracing within its scope features of tooth construction and adjustment.

The significance of attaining an appropriate positioning of the artificial teeth of a denture is generally acknowledged in the art. This is especially important with respect to the coordination of opposing teeth, whether it be between the artificial teeth of one denture, or the artificial teeth which this denture is intended to complement.

This is effectively illustrated by indications that the lack of a suitable harmony between the occlusal or biting surfaces of artificial teeth and opposing natural teeth, such as for example, the condition of interfering or high spots which prevent a satisfactory intercuspding, may result in pyorrhea with the attendant possibility of a loss of teeth. Any expedient directed to the relief of excessive trauma on the natural teeth serves to safeguard those teeth against the danger of pyorrhea developing.

The rectification of such conditions has involved considerable difficulties. Thus where the occlusal surface of an artificial tooth has been unduly low, it has heretofore been necessary to reprocess a denture in order to raise the bite, even of a single tooth, and not infrequently this has failed to fully correct the existing condition, it being necessary to disregard one or more other teeth that are to some extent out of function because of the excessive amount of work involved to entirely eliminate the difficulty.

Moreover, when completed dentures were placed in the mouth, it was almost inevitably found that the occlusion of the teeth—that is—the relationship of the biting surfaces of the upper and lower teeth had changed somewhat during processing from the positions they held when the teeth were retained in wax during the try-in in the patient's mouth. Naturally this change often interferes with intercuspding or height of the teeth so that in order to reestablish a greater biting surface between the antagonistic teeth, the occlusal surfaces require adjustment as by grinding.

This treatment, which is often referred to as "high spot" or "spot" grinding, destroys some of the fine anatomy of the occlusion which is intended for that portion of the tooth.

In case after case we may see many of the valuable cusps that aid in triturating completely destroyed because the teeth had to be ground in order to eliminate interfering high spots.

Many men who realize the importance of proper anatomical carving on a tooth and are a little more particular about this important point, try to recarve some of the anatomy but they find it extremely difficult to restore the original contour which was factory processed in a mold to give the tooth a final polished precision structure, with calibrated inclined planes.

It is an object of this invention to obviate such difficulties and uncertainties as hereinabove described, and to readjust artificial teeth surfaces essentially without any destruction of the fine anatomy.

An object of this invention is to obviate the necessity of grinding and generally mutilating the occlusal or labial surface anatomy of teeth involved in the proper fitting and adjustment of a denture.

Another object of this invention is to provide a tooth adapted for an adjustment of its occlusal surface by the biting or intercuspding action of the patient.

An additional object of this invention is to provide a tooth adapted for readjustment or reorientation at any interval before or after installation and/or usage in a dental plate.

Still another object of this invention is to attain a tooth lowered for adjustment in order to afford normal effectiveness wherein a surface thereof may be oriented, as by raising or lowering for expedient adjustment in order to afford an enhanced effectiveness of tooth function.

Other objects, advantages and features of the invention will become apparent from the following consideration and disclosure, especially when read in connection with the accompanying drawings, the elements of which are discussed hereinbelow.

In accordance with the present invention a tooth is obtainable that has a rigid gingival or lingual portion which softens by heating and a rigid occlusal or labial portion which does not soften at the softening point of the gingival or lingual portion. Thus, the occlusal portion without being injured in any way, can be moved either up or down relative to the softened gingival portion, and similarly the labial portion of an anterior tooth may be oriented with respect to its lingual portion.

There are many materials which are soft enough at reasonable temperatures for molding and yet rigid and hard enough at mouth and food temperatures, from which to make the gingival portion of this tooth. A metal such as "Dialoy" has a softening range from 150° to 170° F. and

makes a suitable base. Similarly, if plasticisers and temperature lowering agents are added to most of the thermoplastic resins, their softening range can be lowered so as to be within reasonable limits for use in this capacity.

The shellac compounds are excellently hard at mouth temperatures and begin to soften at 150° F. Shellac holds the occlusal portion very securely and permits moving the occlusal surface a moderate amount upon softening. Styrene is also an excellent plastic for this purpose and its low softening point is around 170° F.

Teeth made as described comprises any suitable material, such as resins, which soften at 140° F. and under can, with care, be manipulated and adjusted in the mouth. Above that point, this work should be done outside of the mouth. It should be noted that the maximum temperature which can be normally tolerated in the human mouth is approximately 135 degrees F. While there are probably instances where a slightly higher temperature has been withstood in the oral cavity, the maximum in these exceptional cases has never been known to exceed 140 degrees F.

The occlusal portion of this tooth is made from any high fusing material having a high softening point so that it will not distort while being manipulated. Porcelain, metal, the melamine plastics, some of the phenolic resins are examples of such materials.

Thus, when a dentist finds that there is a high point on one of the teeth, he holds that tooth over a flame or softens it by applying locally to that tooth a pledget of cotton with very hot water, and then places the denture quickly back into the mouth and has the patient bite.

This seats the occlusal portion higher in the tooth and forces it into a position where it will not be out of harmony with the other teeth. When the gingival portion of the tooth chills, it is again rigid and holds the occlusal portion firmly.

Corrections can also be made outside of the mouth. The dentist can place the dentures in the mouth and then transfer them onto an articulator, which will carry with it all the error involved. Here, spots that need adjustment can be found quickly, the necessary teeth properly warmed and pressure applied to reseat the occlusal surfaces requiring adjustment.

Or, the dentist may mark the tooth that is high with carbon paper, merely remove the denture, warm the tooth and then, with a blunt instrument, reseat the portion occlusal to where he thinks it should be.

This can be repeated several times, if necessary, until the dentist finds the right spot. If an adjustment has been made that required considerable shortening of the tooth, a mass of the gingival tooth plastic may bulge on the labial and buccal, or even mesial and distal, if there is room for the gingival portion to flow in that direction. When the tooth returns to a normal temperature, and becomes hard and rigid, any superfluous or protruding material can be ground away as is illustrated later on.

In order to more fully illustrate the invention, reference will now be made to the accompanying drawing wherein certain examples are shown by way of illustration.

Figure 1 is a section of a molar from lingual to buccal.

Figure 2 is a similar section of the same tooth showing the adjustment of the occlusal relative

to the gingival portion with protruding or superfluous gingival material.

Figure 3 is the buccal view in elevation of four artificial opposing four natural teeth.

Figure 4 is a similar view to that of Fig. 3 after the four artificial teeth have been adjusted and appropriately harmonized with the natural teeth.

Figure 5 is a cross section from lingual to labial of an anterior tooth.

Figure 6 is a similar view to Fig. 5 after the labial and lingual portions have been relatively readjusted.

A more detailed description of these will now be given, like numerals indicating similar elements on the various figures of the drawing.

Referring now to Figure 1, 3 represents the gingival portion and 4 the occlusal portion of an illustrative tooth. The occlusal surface 5 of the tooth has the buccal cusp 6 and the lingual cusp 7. The numeral 8 indicates the lingual surface of the occlusal portion 4 of the tooth.

This occlusal portion, 4, is made of a hard and rigid material such as porcelain, metal, or high fusing resin, which, when warmed to the temperature required to soften the gingival portion 3 of the tooth, will not become soft and flow, but will remain hard and non-deformable under the necessary pressures and temperatures at which the gingival portion 3 of the tooth is moldable or will flow and yield to pressure. At 9, 16 and 13 are junction points or areas of attachment of the respective hard occlusal portion and the comparatively softenable gingival portion. At 11 is the base part of the softenable gingival material, and 12 is the buccal surface thereof. The buccal surface of the relatively higher softening occlusal portion of the tooth is designated 14. The lingual surface of the occlusal portion is designated 8, while the lingual surface of the gingival portion is represented by the numeral 10.

Figure 2 is a similar view to Fig. 1, but the gingival tooth portion 3 has been heated to the softening point and pressure has been applied on the occlusal surface, from the direction of cusps 6 and 7 toward the gingival portion. This caused the gingival material to be displaced and the tooth to become shorter, with the resultant formation of bulges 19 and 20 on the respective lingual and buccal surfaces. Where there are proximating teeth, this is essentially the only direction the material can flow. Where there are no proximating teeth the flow or displacement may be all directions.

After this tooth becomes the proper length, these bulges of material may be trimmed, and the contour brought back to normal as indicated at 18 and 21. It will be noted that there has been not the slightest change in the anatomy or contour of the occlusal portion 4 of the tooth, so that, although the tooth has undergone considerable shortening, it was not at the expense of the occlusal surface anatomy and the tooth will be able to function as originally intended.

Figure 3 illustrates a most common situation when a new denture is first tried in the mouth. At 30 and 31 are artificial first and second upper bicuspids. Nos. 32 and 33 are artificial first and second upper molars. At 34 and 35 are natural first and second bicuspids. At 36 and 37 are natural first and second lower molars. As is here illustrated, the only portions of the upper teeth that articulate are the upper first molar 32, whose occlusal surface 40 is striking the distal cusp 39 of the first molar, and the mesial cusp of

the second molar 38. It is noted that there is a space 41 between the occlusal surfaces of the other teeth, due, of course, to the height of the cusps 38 and 39.

Prior to this invention it was necessary to cut away much of the anatomical portion of the occlusal surface of tooth 32. Only by spending much time, could the dentist recarve this anatomy after grinding it away, although it is doubtful if it ever could be restored as well as before the tooth was mutilated. Or, this condition shown in Figure 3 could be remedied by carving off the natural cusps 38 and 39, which, of course, in most cases is undesirable.

In Figure 4 is shown how well this difficulty can be corrected pursuant to the present invention. Heat was applied to occlusal portion 40 and to the gingival portion 32. The heat applied to 40 was transferred to the material directly below it so as to soften it and cause it to yield under pressure. Not to have the patient feel it, if higher heat is desired, the tooth can be surrounded by cotton rolls, with only the biting surface exposed. Or, heating can be done outside the mouth, where it is simple to use an instrument to depress or alter the occlusal surface.

Figure 5 illustrates the same principle on anterior teeth. At 50 is the rigid high fusing portion and 51 is the rigid softenable-by-heat material into which 50 can penetrate when an adjustment is desired. At 53 is the labial surface; at 54 the lingual surface.

In Figure 6 the outer, higher fusing portion has been pressed lingually, shortening the tooth. It will be noted that excess material from the lower fusing lingual portion exuded at points 56 on the lingual and 57 on the labial. These, of course, should be trimmed back to points 58 on the lingual and 59 on the gingival and then polished.

Pursuant to the present invention, an artificial tooth structure is attained which inherently lends itself to the desired adjustment and/or orientation of its portions in a manner to facilitate and appropriately fit in a denture and to provide the harmonized association of artificial teeth relative to each other and to opposing teeth, whether they be natural or artificial. This advantageous result is possible without resort to any operation that might cause the destruction of the fine anatomy of tooth surface that is obtainable through the moulding procedure whereby the tooth is made. Moreover, in addition to its significance in the fitting of the artificial teeth, or dentures embracing these teeth, the invention is applicable to teeth or dentures which have been in use, but require readjustment because of the disalignment which may have developed, for example, through the abnormal growth of any opposing natural teeth.

It is accordingly apparent that the invention provides entirely novel and practicable features relating to artificial tooth and prosthetic denture construction and adjustment, substantially eliminating the difficulty and uncertainty heretofore involved in fitting and coordinating the occluding or masticatory surfaces of opposing teeth. A significant attribute resides in the substantial obviation of the necessity for resorting to such expedients as "spot" grinding, or in any manner altering the predetermined occlusal or labial anatomy of a given tooth, whether it be artificial or an opposing natural tooth, in order to attain requisite compatibility between opposing teeth.

Many other features and advantages are at-

tributable to the invention, and it will be obvious that they may be the subject of ramifications and variation without departing from the scope of the invention. While the invention has been described in accordance with desirable embodiments, many changes and modifications may be made in the details of construction and procedure, and in the combination and arrangement of parts, without departing from the spirit of the invention as defined in the following claims.

The term "denture" as utilized herein connotes any appliance either fixedly or removably positioned in or attachable to the oral cavity and adapted to function as a tooth support. It embraces within its purview such devices as plates, bridges, and the like.

What I consider new and desire to secure by Letters Patent is as follows:

1. An integral artificial tooth structure comprising a plurality of portions embodying several materials, each of said portions fabricated from a predetermined material, said materials being adapted for dental prosthesis and manifesting requisite rigidity and hardness at maximum temperatures encountered in the oral cavity, at least one of said materials having a softening temperature at which another of said materials is essentially unaffected, whereby said portions are relatively adjustable at the softening temperature of one of said materials and will retain any such relative adjustment.

2. An integral artificial tooth structure comprising two portions, each portion embodying a material adapted for dental prosthesis and manifesting substantial rigidity and hardness at maximum temperatures encountered in the oral cavity, one of said materials being thermoplastic relative to the other material and having a moldable softening temperature substantially differentiated from any softening temperature of the other material, whereby said portions are relatively adjustable at the moldable softening temperature of said relatively thermoplastic material portion and will retain any such relative adjustment.

3. An artificial tooth molded in accordance with a predetermined contour surface comprising an occlusal portion and a thermoplastic gingival portion, both of said portions being prosthetic dental materials manifesting requisite rigidity and hardness at maximum temperatures encountered in the oral cavity, said gingival portion having a moldable softening temperature at which said occlusal portion is essentially unaffected, whereby said occlusal portion is adapted for adjustment relative to said gingival portion at the softening temperature of the latter and said portions will retain any such relative adjustment.

4. An artificial tooth comprising a labial portion, and a lingual portion having a moldable softening temperature in excess of the maximum temperature encountered in the oral cavity, both portions being materials adapted for dental prosthesis and manifesting rigidity and hardness at maximum temperatures encountered in the oral cavity, the moldable softening temperature of the labial portion being relatively high and the softening temperature of the lingual portion being relatively low, whereby said labial portion may be adjusted relative to the lingual portion at the softening temperature of the latter, and said portions will retain any such relative adjustment.

5. An artificial tooth comprising a thermo-

plastic gingival portion, and an occlusal portion of predetermined masticatory surface and comparatively rigid at the softening temperature of said gingival portion, both portions being prosthetic dental materials hard and rigid at maximum temperatures encountered in the oral cavity, said occlusal portion being superimposed upon said thermoplastic gingival portion in interlocked attachment, whereby said occlusal portion is adapted for adjustment or altered orientation relative to said gingival portion, at the softening temperature of the latter and said portions will retain any such relative adjustment.

6. In a denture, at least one artificial tooth comprising in integral combination a thermoplastic gingival portion attached to said denture and an occlusal portion of predetermined masticatory surface, both portions being materials adapted for dental prosthesis and hard and rigid at maximum temperatures encountered in the oral cavity, said gingival portion being moldably plastic at a temperature above the maximum oral cavity temperature, said occlusal portion being relatively unaffected by heat, whereby said artificial tooth is adapted for length adjustment and realignment relative to an opposing denture at the molding temperature of said gingival portion, said portions retaining any such relative adjustment.

7. The method of adjusting a denture embodying at least one artificial tooth having an occlusal and a thermoplastic gingival portion, said tooth being rigid at maximum temperatures encountered in the oral cavity, said gingival portion having a moldable temperature at which said occlusal portion is unaffected, which comprises supplying heat to said tooth for rendering the gingival portion thereof moldable, adjusting the relative position of said occlusal and gingival portions at the moldable temperature of said gingival portion to correspond with the occlusal surface of an opposing denture and permitting said gingival portion to cool to its rigid state.

8. The method of adjusting artificial teeth of a denture embodying artificial teeth each having a thermoplastic gingival portion attached to said denture, and a thermoset occlusal portion in integral combination with said gingival portion, both of said portions being essentially hard and rigid at maximum temperatures encountered in the oral cavity, said gingival portion having a moldable temperature above the maximum temperature encountered in the oral cavity, said occlusal portion being relatively unaffected by heat,

which comprises heating the tooth to be adjusted to the moldable temperature of the gingival portion, forcing said occlusal portion into harmonious engagement with the corresponding tooth or teeth in the mouth by the biting action of the patient, permitting said gingival portion to become rigid by cooling, and trimming off any resulting contour irregularities in said gingival portion.

9. In a denture at least one artificial tooth comprising in integral combination a thermoplastic lingual portion attached to said denture and a thermoset labial portion derived from a material adapted for dental prosthetics, said lingual portion being a substance adapted for dental prosthetics from the group consisting of metallic materials and resinous materials of natural and synthetic derivation, both portions being materials adapted for dental prosthesis and hard and rigid at maximum temperatures encountered in the oral cavities, said lingual portion being mouldably plastic at a temperature above the maximum oral cavity temperature, said labial portion being relatively unaffected at the softening temperature of said lingual portion, whereby said artificial tooth is adapted for readjustment and for realignment relative to an opposing denture at the moulding temperature of said lingual portion, said portions retaining any such relative adjustment.

10. The method of adjusting a denture embodying at least one artificial tooth having a labial and a thermoplastic lingual portion, said tooth being rigid at maximum temperatures encountered in the oral cavity, said lingual portion having a moldable temperature at which said labial portion is substantially unaffected, which comprises supplying heat to said lingual portion for rendering the same moldable, adjusting the relative position of said labial portion at the moldable temperature of said lingual portion, and permitting said lingual portion to cool to its rigid state.

11. An artificial tooth as in claim 3 wherein the occlusal portion is a thermoset synthetic resin and the gingival portion is a thermoplastic synthetic resin.

12. An artificial tooth as in claim 3 wherein the occlusal portion is porcelain and the gingival portion is a synthetic resin.

13. An artificial tooth as in claim 4 wherein the labial portion is porcelain and the lingual portion is a synthetic resin.

JACOB A. SAFFIR.

Certificate of Correction

Patent No. 2,391,925.

January 1, 1946.

JACOB A. SAFFIR

It is hereby certified that errors appear in the printed specification of the above numbered patent requiring correction as follows: Page 1, second column, lines 28 and 29, strike out the words "lowered for adjustment in order to afford normal effectiveness"; page 2, first column, line 55, for "portion occlusal" read *occlusal portion*; and that the said Letters Patent should be read with these corrections therein that the same may conform to the record of the case in the Patent Office.

Signed and sealed this 21st day of May, A. D. 1946.

[SEAL]

LESLIE FRAZER,
First Assistant Commissioner of Patents.
